(57) **CLAIM**

The ornamental design for a combined cake and muffin carrier, as shown and described.

DESCRIPTION

FIG. 1 is a perspective view of the combined cake and muffin carrier in a first configuration;

FIG. 2 is a left side elevational view of the combined cake and muffin carrier in the first configuration, the opposite side of which is identical;

FIG. 3 is a front elevational view of the combined cake and muffin carrier in the first configuration, the opposite side of which is identical;

FIG. 4 is a top plan view of the combined cake and muffin carrier in the first configuration;

FIG. 5 is a bottom plan view of the combined cake and muffin carrier;

FIG. 6 is a perspective view of an alternate embodiment of FIG. 1, the difference being in the number of holes; and,

FIG. 7 is a perspective view of an alternate embodiment of FIG. 1, the difference being the removal of the hole portion. The broken lines are for illustrative purposes only and form no part of the claimed design.
